[57] CLAIM

The ornamental design for a wrist watch, as shown.

DESCRIPTION

FIG. 1 is a front elevation view of a wrist watch showing
our new design;

FIG. 2 is a right side elevation view thereof, the left side
elevation view being identical to the right side elevation
view;

FIG. 3 is a top plan view thereof, the bottom plan view
being identical to the top plan view;

FIG. 4 is a rear elevation view thereof; and,

FIG. 5 is a perspective view thereof.

FIG. 3

FIG. 1

FIG. 2

FIG.4
